WINDOW HOOD

Filed Dec. 5, 1925

UNITED STATES PATENT OFFICE

DOMINICK J. CARA, OF MEMPHIS, TENNESSEE

WINDOW HOOD

Application filed December 5, 1925. Serial No. 73,452.

This invention relates to certain improvements in window hoods and it is an object of the invention to provide a device of this kind which, when in applied position with respect to a window opening, serves to provide effective protection against rain or snow and wherein the hood is provided with means for effecting a ready discharge of water which may be collected thereby.

Another object of the invention is to provide a hood especially designed for use in connection with a window of a locomotive cab and wherein the hood is provided with a gutter to shed or carry off water which may drip from the roof of the cab, said gutter having its opposite ends open so that when the locomotive with which the hood is in transit air will pass along the gutter in a manner to effectively free the gutter of cinders which would otherwise be liable to collect therein.

The invention consists in the details of construction and in the combination and arrangement of the several parts of my improved hood whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in perspective illustrating a hood constructed in accordance with an embodiment of my invention in applied position;

Figure 2 is a view partly in section and partly in end elevation of the structure as illustrated in Figure 1;

Figure 3 is a view end elevation illustrating a hood constructed in accordance with a further embodiment of my invention.

As disclosed in the accompanying drawings, C denotes the cab of a locomotive provided with the usual windows W and wherein the roof R of the cab projects slightly beyond the side wall S of the cab. Extending along

the side wall S above the windows W is a hood H having each end closed by a plate 1 to provide a mounting for a spring roller 2 of any preferred type and upon which roller 2 is adapted to be wound the curtain 3. The rear edge of the top wall 4 of the hood H is defined by an upstanding flange 5 which is adapted to be secured by a screw 6 or the like directly to the side wall S resulting in the hood proper extending outwardly from said wall. As is illustrated in the accompanying drawing, it is to be noted that the hood H is made from a single sheet of material, the desired parts being preferably formed by stamping.

The top wall 4 of the hood H is disposed on a predetermined downward curvature with the lower marginal portion of such top wall 4 continued by an upwardly disposed or curved flange 7 resulting in the formation of a gutter which will readily shed or carry off water which may drip from the adjacent side of the roof R.

The outer or free end marginal portions of the curtain 3 have operatively engaged with the corners thereof and at a point substantially midway of such corners, the arms 8 which in turn are operatively engaged, as at 9, with the side wall S so that said curtain, when extended, may be disposed in the fashion of an awning and in order to facilitate this particular operation of the curtain, it is to be noted that the lower open face of the hood H is of such width to readily permit the requisite outward movement of the curtain.

It is to be noted that the gutter 7 is open at its opposite ends to permit a ready discharge of water which may be collected in the gutter. Furthermore, by having the ends of the gutter 7 open provision is made for effective blowing out of cinders which may collect within the gutter. This operation is assured as this particular construction of the gutter permits the air to pass therethrough at a rate of speed in accordance with the travel of the locomotive and as the gutter from end to end is constructed in a manner without any intermediate obstructions.

In the embodiment of my invention as illus-

trated in Figure 3, the top wall 4' of the hood H' is substantially semi-circular in cross section with the inner or rear marginal portion of said top wall 4' substantially defined by the upstanding flange 5' which is adapted to be suitably anchored or attached to the side wall S. This flange 5' coacts with the adjacent portion of the top wall 4' to provide a valley or gutter which will readily shed or carry off water which may drip upon the hood from the roof R of the cab.

From the foregoing description it is thought to be obvious that a hood constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In an awning construction, a combined roller hood and supporting bracket, said hood and bracket being integrally formed of a single sheet of material, the connecting edges of said hood and bracket being arcuately bent whereby to provide a gutter therebetween, said gutter having open opposite end portions, the end portions of the hood being extended beneath the ends of the gutter whereby to support the gutter.

In testimony whereof I hereunto affix my signature.

DOMINICK J. CARA.
